CLOSURE

Robert Walker, New Lisbon, Wis.

Application September 28, 1954, Serial No. 458,897

3 Claims. (Cl. 220—32)

This invention relates to a closure, and more particularly to a dust-proof closure for containers holding fluid such as milk.

The object of the invention is to provide a closure or cover which can be readily locked or unlocked on a container and wherein the cover in its closed or locked position will effectively seal an opening without the necessity of using gaskets.

Another object of the invention is to provide a self-sealing dust cover for closing manholes or the like that are in tanks that contain fluid such as milk, there being a clamp provided for preventing accidental opening of the cover.

A further object of the invention is to provide a dust-proof cover which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a longitudinal sectional view taken through the closure of the present invention.

Figure 2 is a top plan view of the closure.

Figure 3 is a fragmentary sectional view of the closure showing the spring clamp.

Referring in detail to the drawings, the numeral 10 designates a body that may be part of a container for holding fluid such as milk, and the body 10 includes a circular flat portion 11 that has a collar 12 extending upwardly and inwardly therefrom, Figures 1 and 3. The collar 12 converges inwardly from the inner edge of the flat portion 11, and the upper end of the collar 12 terminates in a horizontally disposed flange 14. The flange 14 is provided with a circular central opening 15 which may be used for any suitable purpose, as for example for filling the container with fluid such as milk.

A closure is provided for closing the manhole or opening 15, and the closure or cover is indicated generally by the numeral 16. The cover 16 includes a cylindrical main portion 17 and a top portion 18 which may be of arcuate shape. The lower edge of the cover 16 is rolled outwardly and upwardly as at 19 to provide a curved lip, and this lip 19 engages the collar 12 to provide an effective seal between these parts. A means is provided for pivotally connecting the cover 16 to the body 10, and this means comprises a pair of spaced parallel apertured ears 20 which extend upwardly from the flat portion 11 and are secured thereto in any suitable manner, as for example by welding. A pin 21 pivotally connects a finger 22 to the ears 20, and the finger 22 is secured to the main portion 17 of the cover 16 as shown in Figures 1 and 2.

A clamping means is provided for retaining the cover in its closed position, and this clamping means comprises lugs 23 which extend upwardly from the flat portion 11 and are secured thereto, and a pivot pin 24 hingedly connects a hollow casing 25 to the lugs 23. A rod 26 is slidably or reciprocably arranged in the casing 25, and

2

an enlarged head 27 is arranged on the inner end of the rod 26. A coil spring 31 is circumscribed on the rod 26, and the coil spring 31 is interposed between the head 27 and the upper end 32 of the casing 25. Secured to the upper or outer end of the rod 26 is a keeper or arm 28, and the keeper 28 is adapted to have one of its ends engage the upper flat surface 30 of a shoulder 29 which extends outwardly from the cover 16. Thus, with the parts as shown in Figure 3 the cover 16 will be retained in its closed position. Then, when the cover is to be raised or pivoted about the pin 21, it is only necessary to manually lift the keeper 28 and then rotate the keeper 28 slightly to clear the shoulder 29 so that the cover 16 can then be swung open. The coil spring 31 retains the cover closed when the parts are in the position shown in Figure 3.

From the foregoing it is apparent that there has been provided a closure for an opening such as the opening 15. In use the clamp including the keeper 28 will retain the cover 16 in its closed position so that no dust or other foreign matter can pass through the opening 15 into the interior of a container. Thus, a seal is effected between the inclined collar 12 and the rolled lip 19 when the parts are in the position shown in the drawings and the coil spring 31 urges the head 27 downwardly so that the keeper 28 engages the flat surface 30 of the shoulder 29 to prevent accidental opening of the cover. Then, when the cover is to be opened as when the contents of the container are to be replenished or refilled, it is only necessary to manually raise the keeper 28 against the tension of the coil spring 31 and then rotate the keeper 28 slightly so that it clears the shoulder 29. Then, the cover 16 can be raised or swung open.

The lip 19 seats against the collar 12 and the collar 12 is formed at an angle of approximately 10° with respect to the horizontal plane. The dust cover of the present invention is especially suitable for use with tanks containing milk or other fluids whereby manholes in such tanks can be closed. A seal can be effected without the use of rubber or any other gasket material and the seal is effected when the cover 16 is in a horizontal position since the rolled edge 19 contacts with and bears against the collar 12 and the spring clamp maintains the cover at the proper sealing pressure. Since the collar 12 is arranged at an angle of approximately 10°, there will be a continuous seal all around the opening due to the spring clamp.

I claim:

1. In combination, a body including a circular flat portion, an annular collar extending upwardly from the inner edge of said flat portion and converging inwardly, a horizontally disposed circular flange extending inwardly from the upper portion of said collar and provided with a central circular opening, a pair of apertured ears extending upwardly from said flat portion and secured thereto, a cover including a cylindrical vertically disposed main portion having an outwardly and upwardly rolled lip on its lower end forming a gutter for engagement with said collar, and a finger secured to said main portion of the cover and pivotally connected to said ears.
2. In combination, a body including a circular flat portion, an annular collar extending upwardly from the inner edge of said flat portion and converging inwardly, a horizontally disposed circular flange extending inwardly from the upper portion of said collar and provided with a central circular opening, a pair of apertured ears extending upwardly from said flat portion and secured thereto, a cover including a cylindrical vertically disposed main portion having an outwardly and upwardly rolled lip on its lower end forming a gutter for engagement with said collar, a finger secured to said main portion of the cover and pivotally connected to said ears, and means for clamping said cover to said flat portion.

3. In combination, a body including a circular flat portion, an annular collar extending upwardly from the inner edge of said flat portion and converging inwardly, a horizontally disposed circular flange extending inwardly from the upper portion of said collar and provided with a central circular opening, a pair of apertured ears extending upwardly from said flat portion and secured thereto, a cover including a cylindrical vertically disposed main portion having an outwardly and upwardly rolled lip on its lower end forming a gutter for engagement with said collar, a finger secured to said main portion of the cover and pivotally connected to said ears, and means for clamping said cover to said flat portion, said means comprising a shoulder secured to the exterior of said cover and including an upper flat surface, apertured lugs secured to said flat portion, a casing having its lower end pivotally connected to said lugs, a rod reciprocably arranged in said casing and having a head on its inner end, a coil spring

4
circumposed on said rod and abutting said head, and a keeper secured to the outer end of said rod for engagement with the flat surface of said shoulder.
